S. H. RANDALL.
LEATHER CREEPING MACHINE.

No. 357,230.

Patented Feb. 8, 1887.

FIG. 2.

FIG. 3.

FIG. 5.

FIG. 6.

UNITED STATES PATENT OFFICE.

SILAS H. RANDALL, OF WYOMING, OHIO.

LEATHER-CREASING MACHINE.

SPECIFICATION forming part of Letters Patent No. 357,230, dated February 8, 1887.

Application filed October 18, 1886. Serial No. 216,498. (No model.)

To all whom it may concern:

Be it known that I, SILAS H. RANDALL, a citizen of the United States, residing at Wyoming, in the county of Hamilton, State of Ohio, have invented certain new and useful Improvements in Leather-Creasing Machines, of which the following is a specification, reference being had therein to the accompanying drawings.

This invention relates to those leather-creasing machines which include an upper and lower train of rolls, between which the strap is run; and my improvement consists in journaling one of these trains in a swinging frame capable of being thrown back, so as to allow the most convenient access to the operative parts of the machine. I usually journal the upper train in this swinging frame, and operate the latter by a treadle movement, as hereinafter more fully described.

In the annexed drawings, Figure 1 is a front elevation of my improved leather-creasing machine, a portion of the table that supports the same being broken away. Fig. 2 is a plan of the machine, the cords that operate the swinging frame being omitted. Fig. 3 is an end elevation of the machine. Fig. 4 is another end elevation, but showing the frame that supports the upper train of rolls swung back to permit access to the lower train. Fig. 5 is an enlarged end elevation of one of the adjustable journal-bearings. Fig. 6 is a horizontal section of the box of said bearing.

A represents a bed plate or frame, having rigidly attached to its opposite ends the vertical arms B B', supporting a rock-shaft, C.

c c' are pins that rigidly connect the opposite ends of this shaft to a pair of swinging arms, D D', each of which has a front extension, E, a rear prolongation, E', and a pendent stop, F, the members E E' being perforated at e e' to receive thongs or wire cords G G'. These thongs or cords are fastened around the pins c c', and the front ends of said cords have eyes or other devices, g g', for ready coupling to the appliances that retain the swinging frame C D D' in its normal or operative position.

In Fig. 1 a spring, H, is shown as being used for this purpose, while in Fig. 3 the frame is closed by a weight, h, one of the latter being applied to each of the cords G G', the rear ends of these cords being fastened to a bar, I, united by a coupling, i, to a treadle, J; but in

some cases it may be preferred to attach the front ends of the cords G G' to a common bar, similar to that just described, and connect this bar to the floor by one or more springs of any suitable construction. Each swinging arm has a pair of lugs or ribs, k k', bearing against two sides of a sleeve, L, which sleeve is held in contact with said lugs by a screw, K, tapped into the stop F of said arm. Journaled in these sleeves is the shaft or mandrel M of the upper train of rolls, N, which latter may have any approved form of creasers, as suggested at n; but as said flanges are old and well known, further description of them is unnecessary.

O represents the shaft of the lower train of rolls, P, said shaft being journaled in sleeves L', similar to those previously described. This lower pair of sleeves, L', is fitted in the vertical arms B B', each of the latter being provided with a pair of lugs or ribs, r r', and set-screws R, to retain said sleeves in place. Furthermore, the front portions of said vertical arms B B' have horizontal screws S S and vertical screws T, which latter regulate the closure of the arms E E'. The upper shaft, M, has a pinion, m, that gears with a pinion, o, of the lower shaft, the latter being turned by a crank, U.

V is a table that supports the machine.

W is a stripper that prevents the strap adhering to the rolls.

X is a gap in the swinging arms D D' to admit the sleeve of the upper shaft, and Y is a similar gap in the vertical arms B B' to admit the sleeve of the lower shaft.

In fitting up this machine, the bed-plate A is first secured to the table or work-bench V, and the rear ends of the wire cords or other flexible connections G G' are fastened to the opposite extremities of the common bar I. The cord G is then passed up through the hole e' in the rearward prolongation, E', of the swinging arm D, and said cord is fastened around the pin e. The cord is now passed down through the hole e of the front extension, E, of said arm, and the eye g of said cord is engaged with the appropriate end of spring H, or with a suitable weight. The other cord, G', is then applied to the opposite arm, D', in a similar manner, thereby causing the arms D D' to be closed by the stress of spring H, the degree of closure being regulated by properly adjusting the ver-

tical screws T. The ordinary opening of these arms, for the purpose of admitting a trace or other strap, is regulated by the horizontal screws S, which can be set so as to cause their 5 inner ends to come in contact with the stop F of said arms. These adjustments having been effected, the operator depresses the treadle J, thereby raising the front ends of arms D D' until their stops F come in contact with the 10 points of screws S, which act elevates the upper train of rolls, N, a sufficient distance to permit the ready insertion of the strap in the machine. Treadle J is then liberated, thus leaving the spring H free to pull down the front 15 end of the arms as far as the screws T will permit. The strap is then run through the machine in the usual manner, the surface of the leather being creased by the circumferential creasers n of the rolls N.

20 If it should be desired to inspect, change, or repair either train of rolls, the cords G G' are first detached from the spring H, and the swinging frame C D' is thrown back to the position seen in Fig. 4, thus affording the most 25 convenient access to all parts of the machine. Any wear, either of the shafts or the sleeves within which they are journaled, can be readily taken up by slackening the proper set-screw K or R and then shifting the sleeve, after which said screw is again tightened.

30 It is evident the slackening of these screws permits the bodily removal of the shafts M O at the appropriate gaps X Y, and without detaching any other part of the machine. Ref-

erence to Fig. 5 shows that the bearing r for 35 the sleeve L is about vertically under the center of the same, while the other bearing, r', is horizontally in line with said center. It will also be seen that the set-screw R is applied to the opposite side of the sleeve and about at an 40 angle of forty-five degrees thereto. Consequently, these five bearings, r r' r' R hold said sleeve very securely and prevent it shifting either longitudinally or circumferentially within the vertical arm B'. Finally, it is apparent 45 the swinging arms D D' may be applied to the lower instead of the upper train of rolls, and may be cast in one piece with a longitudinal bar that would take the place of the rock-shaft C.

I claim as my invention—
The combination, in a leather-creasing machine, of two trains of rolls driven by suitable 50 gearing, one of said trains being supported by and between two journal-boxes, each of which is applied to one of a pair of rigidly-united 55 stationary arms, while the other train is supported by and between two journal-boxes, each of which is borne by one of a pair of rigidly-united arms hinged to the previously-mentioned 60 stationary arms, all arranged to operate substantially as herein described.

In testimony whereof I affix my signature in presence of two witnesses.

SILAS H. RANDALL.

Witnesses:

JAMES H. LAYMAN,

SAML. S. CARPENTER.
